UNITED STATES PATENT OFFICE.

FRANK GADE, OF FREDSVILLE, IOWA, ASSIGNOR OF ONE-HALF TO ANDREW M. HANSEN, OF CEDAR FALLS, IOWA.

BOTTLE.

1,085,251.

Specification of Letters Patent.

Patented Jan. 27, 1914.

Application filed March 6, 1913. Serial No. 752,406.

To all whom it may concern:

Be it known that I, FRANK GADE, a citizen of the United States of America, and a resident of Fredsville, Grundy county, Iowa, 5 have invented certain new and useful Improvements in Bottles, of which the following is a specification.

My invention relates to improvements in bottles, and the object of my improvement 10 is to supply a bottle or other receptacle with means for suitably controlling its vent passage to permit the emptying of the contents thereof after filling, but to prevent the successful refilling thereof after emptying. 15 This object I have accomplished by the means which are hereinafter described and claimed, and which are illustrated in the accompanying drawings, in which:

Figure 1 is a central vertical section of a 20 bottle equipped with my improved means for preventing refilling thereof, and Fig. 2 is a horizontal section of such means taken on the line *a*—*b* of said Fig. 1.

Similar numerals of reference denote 25 corresponding parts throughout the several views.

The bottle or jar 1 is shown as having a relatively large neck 2 for purposes of convenient representation and description, but 30 the neck may be smaller or of different form and its passages inclined in other ways without departing from the principles of my invention.

The neck 2 is integral with the body 1 of 35 said bottle, and is provided with a vent passage comprising the communicating channels 3 and 4 of which the channel 4 is at once the more contracted in diameter and of less height, with its junction to the other 40 channel preferably in the form of an annular downwardly concaved shelf to whose curved contour the valve 5 is conformed to fit it closely. The upper channel 3 is cylindrical throughout. An inclined cylindrical pit 13 extends into said neck 2 from its 45 upper surface, for a distance. The numerals 10 and 11 denote two passages slightly inclined to the horizontal and which lead from the vent 3, in a slightly divergent way 50 to bend around the pit 13 to communicate therewith just above its bottom and at its side nearest the hither side of the neck, as best shown in Fig. 2.

The bottle may be filled through the open 55 channels 3—4 in the usual manner. Then

the valve-body 5 is deposited in the channel 3 to rest fittingly upon the concaved shelves thereof, which closes the channel 4 when the bottle is upright. The valve-body has a convex lower face, and if it is pressed out of 60 metal its upper face may be concave, and has integral upstanding marginal lugs 6 which contact with the inner wall of the channel 3, to keep the valve at a right angle to said walls when moving back or forth in 65 the channel and prevent its binding or overturning, which would nullify the action of the closing means.

The bottle being filled, and the valve-body deposited on its seat as shown in Fig. 1, the 70 upper end of said channel 3 is permanently closed by a stopple 8, which may be of glass or other suitable material. The wall of said channel 4 as also the abutting part of said stopple 8 are supplied with registering 75 notches which together form an opening or pit, and this pit may be filled with molten glass which produces a key 9 in the shape of an inverted wedge to lock the stopple to 80 said channel, preventing removal of the stopple without breaking the wedge and the 85 bottle neck, thus destroying the usefulness of the bottle for refilling. The stopple has an integral depending central projection 7 whose use will be hereinafter described, and 90 whose end is located approximately opposite the center of each of the openings of the passages 10 and 11 into the channel 3. When the stopple has been thus secured, a metal cap 14 may be fitted over the neck 90 with its edge crimped over the terminal bead of the neck, or in lieu thereof a cork may be placed in the pit 13.

To empty the contents of the bottle, the latter is tilted or inverted enough to cause 95 the valve-body 5 to move along the channel 3 under the influence of gravity, to a position where its upper flat surface will contact with the stop-finger 7, this position of the valve being indicated by dotted lines in 100 Fig. 1. In the latter position, the marginal edge of the valve lies nearly medially across the openings of the passages 10 and 11 into the channel 3. The contents of the bottle may then escape through said passages 10 105 and 11 and the pit-vent 13. If the bottle be now returned to its upright position, the valve 5 will fall back to its first position to close the channel 4 and prevent the refilling of the bottle. If the bottle is laid on its 110

side or be inverted, the valve-body 5 will move toward the stop-finger 7 which will limit it to the position shown, where its marginal edge will divide the inner openings of the channels 10 and 11 about evenly on both sides of the valve. If the attempt is made to inject a liquid through said openings, it will be seen that the inflowing stream will be divided by the sharp margin of the 10 valve so that a part will fill the small space between the valve and the stopple 8, and that only an equal small amount of liquid can enter the channel 3 below the valve before the pressure on the upper face of the 15 valve will cause the valve to move toward its seat, thus cutting off the openings of the passages 10 and 11 from said channel. Since only a few drops of liquid may then enter the channel 3 below the valve at a 20 time, the attempt to refill the bottle becomes impracticable, since in order to completely fill the bottle, it would have to be restored to its first position and then inverted, very many times, while after a little liquid had 25 entered the channel 4, it would act as a seal to inclose the air above it, and cause an increasing back-pressure from the confined air, which would prevent the bottle being filled.

Having described my invention, what I 30 claim as new, and desire to secure by Letters Patent, is:

1. The combination with a bottle neck having a channel therein providing communication between the exterior and interior of the bottle, of a solid valve movable 35 in said channel and limited in its travel in both directions, a stopper sealed into the outer end of said channel, said neck having a conduit leading from said channel at a 40 point below its upper end to provide communication with the exterior of the neck, said valve being limited in its travel toward said stopper so that it will expose a portion only of said conduit.

2. The combination with a glass bottle-neck having a channel therethrough, of a solid valve movable therein and limited in its travel to and fro, a glass stopple sealed into the outer end of said channel at a point 50 spaced from the limit of travel of said valve in that direction, and a conduit being pro-

vided in said neck extending therethrough from its exterior to communicate with said channel at a point in the latter where it may extend to opposite sides of said valve 55 when the latter is at its limit of movement in one direction.

3. The combination with a glass bottle-neck having a channel therein, of a solid valve movable and fittingly seated in said 60 channel and limited in its travel therein in either direction, a glass seal in the outer end of said channel secured to its inner wall, and a conduit extending from a medial part of said port on one side to the exterior of 65 the bottle neck, said conduit having its outer end set at an angle to the top of the neck and extending downwardly with a closed lower end, the other part of the conduit being divided into two parts both opening into 70 said first-mentioned channel and both opening into the first-mentioned part of the conduit at a point above its bottom and on the side farthest from the said first-mentioned channel.

4. The combination with a glass bottle-neck having a channel and a valve-seat therein with concave upper face, of a solid valve in said channel having a convex lower face adapted to fit said valve-seat and said valve 80 being movable in said channel and having a plurality of small spaced projections thereon lying along the wall of the port to keep it alined therein, a glass body sealed into the outer end of said port to form a frangible 85 stopple therefor and having a central depending integral finger on its lower surface adapted to limit the travel of said valve to space it therefrom, and a conduit extending from said port from a point spaced from its 90 upper end and in communication with the exterior of the neck, said conduit being bent in its course, and opening into said port partially above the upper limit of travel of said valve.

Signed at Waterloo, Iowa, this 18th day of Feb., 1913.

FRANK GADE.
